UNITED STATES PATENT OFFICE.

JOSHUA EVERED, OF DULUTH, MINNESOTA, ASSIGNOR OF TWO-THIRDS TO LOUIS G. LANGE, OF SAME PLACE, AND ALBERT C. LANGE, OF MUSKEGON, MICHIGAN.

STEAM LOG-TURNER.

SPECIFICATION forming part of Letters Patent No. 576,663, dated February 9, 1897.

Application filed April 17, 1893. Serial No. 470,779. (No model.)

To all whom it may concern:

Be it known that I, JOSHUA EVERED, a citizen of the United States, residing at Duluth, county of St. Louis, State of Minnesota, have 5 invented a certain new and useful Improvement in Steam Log-Turners; and I declare the following to be a full, clear, and exact description of the invention, such as will enable others skilled in the art to which it pertains to make 10 and use the same, reference being had to the accompanying drawings, which form a part of this specification.

My invention relates to log-turners for saw-mills, and to that class more especially known 15 as "steam log-turners;" and it consists in the peculiar arrangements and combinations hereinafter described and claimed.

In the drawings, Figure 1 is a vertical elevation, partly in section, of my device, with 20 means for operating the valves omitted. Fig. 2 illustrates the valve-operating mechanism. Figs. 3, 4, and 5 represent special details of the same.

Similar letters refer to similar parts.

25 In the drawings, A represents the floor of a sawmill.

B represents the log-deck.

C is an outline representation of a log-carriage in its relation to the log-carrier.

30 D represents a toothed bar or a bar carrying teeth which is intended to engage and roll the log in the manner common to all devices of this character.

G represents a guide adapted to be moved 35 on post E by means of flanges g g', which grasp the post in a manner common to such constructions. If desired, two posts can be used in the place of one and the cross-head G be carried between them by means of suitable guides. As the form of such constructions is common and well known, I do not deem that it is necessary to describe them in minute details.

45 The toothed bar D is pivoted to the upper end of the cross-head G in such manner that its upper extremity has a backward and forward movement, the forward movement permitting it to come to a perpendicular toward the log-carrier, and its backward movement, 50 in the position shown in the drawings, en-

ables it to reach and engage a log behind the same when located upon the log-deck and in readiness to be moved over the stop thereon onto the log-carriage.

The cross-head G has a bracket G' of convenient length extending from it and to the outer end of which is rigidly attached a hollow piston-rod H. Underneath the outer end of this bracket is mounted upon an appropriate foundation a steam-cylinder I, the upper 60 end of which carries a cylinder-head J and a stuffing-box, the latter being of the usual form.

Passing through the cylinder-head J and longitudinally movable therein is the hollow 65 piston-rod. At the lower end of this piston-rod there is firmly attached thereto a piston-head K of peculiar construction and which in itself is also an auxiliary steam-cylinder. The movement of the piston-head K, through 70 its connection by means of the hollow piston-rod H to the cross-head G, would compel the cross-head to travel upon the guide E to the extent of the movement of the piston-head within the cylinder, and by means of the attachment of the lower end of the tooth-bar to the cross-head G would also compel the movement of the tooth-bar perpendicularly to the same extent.

Projecting from the rear side and lower end 80 of the tooth-bar proper is a bracket L, the outer end of which is attached at L' to a link L². The upper end of the link at L³ is attached to a piston-rod M. This piston-rod is inserted in the hollow piston-rod H, passing 85 through a stuffing-box at the point of the attachment of the hollow piston-rod H to the bracket upon the guide G. As the stuffing-box is of the usual form no detailed description of it is required. The lower end of the 90 piston-rod M is rigidly connected to a piston M' within the hollow piston-head or auxiliary cylinder K. This auxiliary cylinder permits sufficient throw of the piston M' to oscillate (by means of the piston-rod M and the connections through the bracket L to the toothed bar) the tooth-bar, as required in transferring the logs from the log-deck to the log-carriage in a manner that will be hereinafter described. It also permits the tooth-bar to oscillate in 95 100

rotating the log against the knees of the log-carriage due to irregularities in the size or shape of the log thus rotated. The lower end M^2 of the piston-rod M is hollow, the perforation therein extending through the piston-head. Located within this hollow is a steam-pipe N , which is rigidly fastened through the bottom head of the main cylinder I at N' . The lower head of the auxiliary piston-cylinder is bored out to receive it at N^2 , leakage of steam at that point being prevented by a steam-gland N^3 and appropriate stuffing. The movement, therefore, of the auxiliary cylinder upon the pipe N is exactly the same as the piston-rod of a steam-cylinder is through the cylinder-head, with the exception that it is the head which moves, and not the piston-rod. The pipe N extends upward far enough so that it is never withdrawn from the auxiliary cylinder-head. Steam is admitted to the interior of and below the piston-head K of the auxiliary cylinder by means of the pipe N , it being obvious that steam, if admitted to the pipe N , would flow from the top of the same in the hollow of the interior piston-rod M , thence downward and underneath the piston in the auxiliary cylinder, the pressure causing it to rise to the extremity of its allowable motion. It is also obvious that by exhausting the steam from the interior and under side of the piston it will fall downward to its original position by gravity, as shown in the drawings. It is also obvious that by means of connections the raising of the auxiliary piston in the auxiliary cylinder will oscillate the upper end of the tooth-bar to correspond, and that this would be the case at any portion of the stroke of the piston-cylinder within the cylinder I .

$P P'$ are ports connected by appropriate passages $P^2 P^3$ to a steam-chest S . These ports lead into the main cylinder I at positions above and below the stroke of the auxiliary piston-cylinder.

$R R'$ are by-passages leading from the ports to the extreme ends of the cylinder I . These passages are relatively very small and permit the passage of steam in either direction comparatively slowly, and their object is to permit the cushioning of the auxiliary piston-cylinder at either end of its stroke, it being obvious that as steam is admitted at either end of it, if the auxiliary piston-cylinder has passed by and cut off the main passage, steam will be admitted under it or above it by the auxiliary passage, and it will be forced to move until it uncovers the main passage, which will permit the admission of steam much more quickly. As it reaches the opposite end and passes by and cuts off the main port, steam is compressed between it and the cylinder-head, the auxiliary port being insufficient to permit the steam to pass out with sufficient rapidity, and thus the further motion of the piston is arrested gradually by an elastic medium. This is an old and well-

known form of construction and does not form any part of my invention. For the purpose of securing these motions in their relation to each other, I have devised a new and important improvement in valve construction. Adjacent to the main cylinder is a steam-chest S , carrying two piston-valves S' and S^2 in appropriate seats. One valve, S' , is designed to control admission to and exhaustion from the main cylinder, and the other, S^2 , connects with the auxiliary piston-cylinder. These valves are controlled by appropriate valve-rods s and s' , connected with them, respectively. The valve S' is hollow throughout nearly its whole extent.

Surrounding the seating of the valve-stem in its upper end is bored a number of holes, all of which taken together have a greater area than the steam-port. These holes permit a free communication between the interior of the hollow in the valve and the upper end of the steam-chest, in which the valve is located. The central portion of the valve is cut out circumferentially, so as to be of less diameter than the two ends. This forms at that portion a free passage entirely around the valve.

Leading to the steam-chest is a steam-pipe S^3 , which is connected with any suitable source of steam-supply. The orifice from this pipe at S^2 is so situated that it opens directly into the space surrounding the central portion of the valve, and the throw of the valve is also so proportioned that such opening always communicates with that central space, it being closed off from either end of the valve, which is by the two heads of the valve, which are steam-tight, within the steam-chest.

Leading from the steam-chest are the two ports hereinbefore described, $P P'$, but in such relation to the ends of the steam-chest and to the throw of the valve that they are passed upon either side, respectively, by the heads of the valve. Leading from the lower end of the steam-chest is the exhaust-pipe T . This is adjusted so that its orifice opens into or leads from the interior or hollow in the valve hereinbefore described.

With reference to the valve S^2 it is a similar construction to that of the valve S' , its central portion being turned down so as to form a circumferential recess. This, however, is not necessary in this valve, as it might be a plain D -valve. The induction-port, however, opens into the annular space which surrounds the valve in all positions in which it may be placed, the port, however, leading into the auxiliary cylinder through the pipe N and being so situated with relation thereto that it may be closed off when the valve is lifted by means of the lower head of the valve sliding over its opening, and as the valve continues to be raised the port is allowed to open into the space below it. A similar induction-pipe is located at the end of the valve-chest and which, when the valve is

raised, necessarily communicates with the port P and pipe N, permitting the steam within the auxiliary cylinder to escape thereby.

It is obvious that with the valve S' in the position in which it is shown there is free communication from the upper portion of the cylinder I and above the auxiliary piston-cylinder through the port P to that portion of the steam-chest above the valve through the holes hereinbefore described and the perforation in the center of the valve to and through the eduction-pipe T, thus permitting steam to exhaust from the upper end of the cylinder I through the steam-chest and through the valve itself, while at the same time steam is permitted to enter by means of the induction-pipe S³ into the steam-chest and the annular space surrounding the central portion of the valve S', thence through the port P into the lower portion of the cylinder I and underneath the auxiliary piston-cylinder, thereby compelling it naturally to rise, carrying with it the cross-head and the pivoted tooth-bar, performing whatever work it may be adjusted to do. The raising of the valve S' to the extremity of its throw would reverse these conditions, as it opens communication with the upper port to the annular space surrounding it, and thence connecting with the induction-pipe. Simultaneously the lower port opens into the steam-chest below the valve and in direct communication with the eduction-pipe. In this manner steam is exhausted from the lower portion of the cylinder and permitted to enter the upper portion, thereby compelling the auxiliary piston-cylinder to descend therein and with it its attachments. The operation of the valve S² is simpler, as not being connected with a double-acting cylinder, but only with a single-acting cylinder. In the position shown in the drawings it permits free communication by means of the annular space surrounding it between the eduction-pipe and the pipe N. On raising it it first cuts off this communication, then afterward, by still farther raising it, opens the mouth of the pipe N and permits its contents, together with that of the auxiliary cylinder, to escape into the lower portion of the steam-chest and from thence into the eduction-pipe T. In order to operate these valves, I have devised a mechanism shown in Figs. 2, 3, 4, and 5; Fig. 2 being an elevation, partly in section; Fig. 3 being a detailed view of the gimbal-joint carrying the operating-lever, as shown in Fig. 2; Fig. 4 being a detail view of the connecting-rod between the lower portion of the lever and bell-crank connections; Fig. 5 being a detail view of the bell-crank connection. In these drawings U represents a lever which is pivoted in a mortise in a rock-shaft U'. This rock-shaft rotates in bearings U² U³. It is obvious that this mode of attachment of the lever would give it a universal movement or constitute a universal joint substantially the same in principle as a ball-bearing. A ball-bearing might

be substituted for it without departing from my invention. At the lower end of the lever U there are turned two bearings, on which are adjusted two connecting-rods V V'. A small hole u at the bottom permits the introduction of a pin, compelling the retention of the connecting-rods upon the lower end of the lever U. The opposite ends of these connecting-rods are connected by rotating bearings to bell-cranks X X, the opposite end of the bell-cranks being connected to the upper ends of the valve-stems S S'. It is obvious that as the connecting-rods V V', at their point of attachment upon the lever U when the lever U stands perpendicularly, are at right angles the movement of the lever in the longitudinal direction of one of the connecting-rods and transversely as to the other would operate the bell-crank connected to the lever that is moved longitudinally, but would not operate the bell-crank connected to the connecting-rod, the end of which is only moved transversely.

That the reverse motion would operate the opposite bell-crank, and that out of the two motions any combined relative operation of the two bell-cranks could be obtained, and as the valve-stems are connected therewith, it is obvious that the valves would be moved accordingly and that thereby steam would be admitted or discharged, or admitted or discharged relatively into either the main cylinder I or the auxiliary piston-cylinder K, as might be desired by the operator.

The further description of this device, in view of the detailed operation of its several parts, is unnecessary.

Having thus described my invention, what I claim is—

1. In a log-rolling machine, the combination of a toothed bar pivoted at its lower end to a vertically-guided cross-head rigidly attached to the piston-rod of an upright cylinder, the toothed bar having a bracket at its lower end which is radially connected to the piston-rod of an auxiliary cylinder formed within the piston-rod of the main cylinder, both cylinders being operated by suitable steam-valves, levers, and connections, so that the toothed bar may be elevated or depressed and independently oscillated, substantially as described and for the purpose set forth.

2. In a log-turner, the combination of a cylinder, two pistons working therein, and a bar for operating on the log, connected with both pistons, substantially as described.

3. In a log-turner, the combination of a cylinder, two pistons working therein, a bar for operating on the log, and connections between the pistons and operating-bar, one of said pistons being connected to the bar near the lower end thereof, and the other to a lateral extension of the same, whereby the pistons may move said bar laterally, substantially as described.

4. In a log-turner, the combination of a cylinder, two pistons working therein, a toothed

bar connected with both pistons, and inlet and exhaust ports arranged to admit or exhaust steam or other operating fluid at any portion of the stroke, substantially as described.

5. The combination in a log-turner, of a cylinder, two pistons working therein, a bar for operating on the log having a lateral extension pivotally connected with one of the pistons and a link connecting it with the other, substantially as described.

6. The combination in a log-turner, of a bar for operating on the log, a cylinder, two pistons working therein a hollow piston-rod con-

nected with said bar, a second piston-rod working in the hollow piston-rod and connected with and adapted to actuate said bar, a steam-supply and steam-conduit leading therethrough, and a telescopic connection between the steam-conduit and hollow piston, substantially as described.

In testimony whereof I sign this specification in the presence of two witnesses.

JOSHUA EVERED.
